UNITED STATES PATENT OFFICE.

WM. T. NICHOLSON, OF PROVIDENCE, RHODE ISLAND.

EGG-BEATER.

Specification of Letters Patent No. 32,886, dated July 23, 1861.

To all whom it may concern:

Be it known that I, WILLIAM T. NICHOLSON, of the city and county of Providence, in the State of Rhode Island, have invented 5 a new and useful Improvement in Egg-Beaters; and I do hereby declare that the following specification, taken in connection with the drawings, making a part of the same, is a full, clear, and exact description thereof.

Figures 1 and 2 are respectively front and side views of my improved egg beater. Fig. 3 is a view of the chair or socket for attaching the beater to the table or to any 15 other object. Figs. 4 and 5 are detailed parts to be referred to hereafter.

A. A is a convenient handle in which the point B is an axle for the wheel C which is operated by the crank D. The 20 wheel C has its face beveled and provided with teeth which engaging with the teeth of the pinion E. cause the latter to be rotated in a plane perpendicular to the plane of revolution of the former.

The pinion E is keyed to a rod F which has its support and bearings in the handle A at the points a and b (Fig. 2.) The lower 25 extremity of the rod is provided with a pair of propeller blades G. G. which being attached to the rod are rotated with it.

To the under side of the pinion E is secured the disk H (Fig. 5,) its lower surface being furnished with an elliptic groove or channel I. Two arms K. K pivoted to 35 the handle at c and d extend to the bottom of the propeller blade their lower extremities being in the form of a spoon bill's beak. A projecting ear e, e on each arm is inserted in the elliptic groove I whereby as the propeller shaft F is rotated to which the disk

is attached a reciprocating motion is given to each of the arms; the grooved disk being arranged on the shaft F with its longest diameter in the same plane as the propeller blades for the purpose of accommodating 45 the reciprocating motion of the spoon bill arms to the rotary motion of the blades, without interference.

It is obvious that when the machine is in use for agitating fluids the circling currents 50 occasioned by the blades of the propeller will be broken at regular intervals by the action of the spoon bill arms K K in such a manner as to cause the agitation of every particle of the liquid within the range of the 55 action of the machine.

For the purpose of attaching the machine to any object or to any part of the room I use a socket or chair (Fig. 3) which by means of the spurs f f and a single wood 60 screw inserted through the hole g may be permanently affixed wherever desired. The sides h h are slightly inclined toward each other and are also turned over far enough to grasp the handle of the machine which 65 is fitted by a corresponding inclination of its sides to be inserted in the groove of the chair. By raising the handle out of the chair the machine can be removed at pleasure and used as a hand machine. 70

What I claim as my invention and desire to secure by Letters Patent is—

The reciprocating beaters K K or their equivalents when combined with a revolving beater G G or its equivalent—substantially 75 as described for the purposes specified.

WM. T. NICHOLSON.
